JUSTIFYING TYPEWRITER

Oluf G. Oswold, Rochester, N. Y., assignor to International Business Machines Corporation, New York, N. Y., a corporation of New York

Application October 15, 1947, Serial No. 780,077

2 Claims. (Cl. 197—84)

1

This invention relates to typewriting machines. The primary object of the present invention is to provide an improved justifying mechanism for typewriters and other typographical machines.

An object is to provide a justifying mechanism which is automatically set by movement of a typewriter carriage to produce a justified line when the copy is retyped.

An object is to provide an automatic justifying mechanism which is simple and has few parts to get out of order.

An object is to provide an automatic justifying mechanism which may be readily applied to present commercial typewriters without extensive alteration of the machine.

Other objects of the invention will be pointed out in the following description and claims and illustrated in the accompanying drawings, which disclose, by way of example, the principle of the invention and the best mode, which has been contemplated, of applying that principle.

Fig. 1 is a diagrammatic view in perspective showing portions of the carriage of a typewriting machine and certain parts connected thereto and shows the justifying mechanism set in neutral or non-justifying position.

Fig. 2 is a similar view showing the justifying mechanism set in a justifying position.

In order to simplify the disclosure and more clearly show the invention, Fig. 1 discloses parts of a typewriting machine in diagrammatic form and separated in such a manner as to more clearly show the relation of the parts and thus is a form of exploded view.

It will be understood that any suitable typewriter may be used but that one of the type disclosed in Patent No. 2,165,301 may be selected for purposes of disclosing the invention. This patent discloses a machine having provisions for mounting a hektograph tape with the charged side facing outwardly away from the platen. For purposes of the present invention it will be understood that the machine is equipped with a plain paper tape, instead of a hektograph tape, which extends across the writing line to enable a draft of each line which is justified to be written before typing that line on a work sheet on the platen. After this line has been written in unjustified form, the frame carrying the paper tape will be swung upwardly and the operator will recopy the line from the tape in justified form, thereby enabling each line to be proof-read and justified immediately before going on to the next line.

In the drawings 10 represents a portion of the typewriter carriage on which is rotatably

2

mounted the usual platen 11 and the tape supporting arms 12 which may be pivoted at 13, as in the above patent, to a part of the carriage frame. As in the patent, suitable mechanism 5 may be provided to hold the arms 12 in an elevated position when raised. The arms 12, in any suitable manner, support a plain tape T which extends across the writing line on the platen 11 when the arms 12 are lowered as shown in Fig. 1. 10 In the present case the usual carriage rack 14 is not secured to the carriage 10 as in the patent but is slidably mounted on the carriage by suitable means, such as the studs 15 and slots 14a which permit the carriage rack 14 to have limited movement relative to the carriage 10, parallel with the letter spacing movement thereof. The usual carriage spring drum 16 is connected by a tape 17 to the carriage 10 in any suitable fashion. The carriage rack 14 is controlled by an escapement 15 mechanism, not shown, which may be connected to the rack 14 by a suitable pinion 18. It will be understood that, with the exception of the mounting of the rack 14 for relative movement, any of the details described above may take any of the forms well-known in the art as the present invention does not reside in such details of construction.

The rack 14 may be provided with a suitable extension or bracket 14b on which is pivoted at 14c a bell crank 19. One of the arms of the bell crank 19 extends transversely of the rack 14 and is connected to the carriage 10 by a link 20 pivoted at 10a to the carriage 10. The other arm of the bell crank 19 extends approximately parallel with the rack 14 and is pivotally connected at 21a to a shoe or block 21 riding in a groove 22a formed in a track 22. This track is pivoted at 23a to a fixed bracket 23 which may be secured to a convenient part of the main framework of the typewriter. At its left hand end the track 22 is provided with a circular rack 22b which meshes with a pinion 24 secured to a notched locking disk 25. The pinion 24 and the locking disk 25 are journalled on a suitable fixed part of the main framework as by means of a pivot pin 26. A torsion spring 27 which may be connected to the pinion 24 and to a fixed part of the machine tends to rotate the pinion 24 and locking disk 25 in a counterclockwise direction (Fig. 1).

Cooperating with the locking disk 25 is a locking pawl 28 pivoted at 29 to a fixed part of the framework and urged in a clockwise direction into engagement with the notches in the locking disk 25 by a spring 30. The locking pawl 28 is connected by link 31 to a bell crank 32 pivotally

mounted at 33 to a fixed part of the machine. A justifier key 35 is connected by a link 36 to the other arm of the bell crank 32. When the justifier key 35 is pushed inwardly, the locking pawl 28 will be disengaged from the locking disk 25, permitting the spring 27 to restore the track 22 to the normal or non-justifying position shown in Fig. 1, if it is not in that position, as determined by a suitable fixed stop, such as the lug 37 which may be mounted on or form part of the main framework.

In Fig. 1 the track 22 is shown in the non-justified position with the groove 22a extending parallel with the carriage rack 14 and the carriage is assumed to be in the left hand marginal position. In this position, the pivot 21a for the shoe 21 is co-axial with the pivot 23a for track 22 whereby the track is free of restraint of the bell crank 19 and may be freely rotated on the pivot 23a by the spring 27. This permits a relatively light spring to be used in restoring the track 22 to the position shown in Fig. 1, it being merely necessary to return the carriage by means of the carriage return key or by hand until arrested by the marginal stop and then press the key 35 inwardly. If the track 22 is not already in the position shown in Fig. 1 but is in a justifying position as in Fig. 2, the spring 27 will rotate the locking disk 25 and pinion 24 counterclockwise and hold the track 22 lightly against the stop 37.

With a work sheet W in place on the platen 11 and the arms 12 in lowered position the operator proceeds to type the first line of the draft to be copied on the tape T, which is now interposed between the work sheet W and the types. When the carriage comes within a short distance of the right hand marginal position, the right hand marginal stop will trip the usual bell to warn the operator that she has only a few letter spaces left in which to complete the last word in the line. Conveniently the bell tripping mechanism may be so arranged that the bell is sounded within say ten letter spaces of the desired right-hand margin. The operator now proceeds to finish typing a word that can be completed in the remaining space or types a hyphen, if the word is to be split, and presses the justified key 35.

In the process of typing the line on the tape T, the carriage 10 and the rack 14 will travel as a unit to the left to the position of Fig. 2, which represents an arbitrary position within the zone of ten letter spaces selected by setting the usual right-hand marginal stop. During the leftward movement of the carriage, the shoe 21 will travel along the track 22, riding in the slot 22a. Since the track 22 is now parallel with the rack 14, the movement of the bracket 14b to the left will cause the carriage 10 and the rack 14 to travel together since, during this time, the bell crank 19 is restrained from rotating on the pivot 14c. Thus the carriage 10 and rack 14 are mechanically tied together with the link 20, the carriage being subject to the influence of the spring motor 16 and the escapement mechanism in the usual way.

When the carriage reaches the position of Fig. 2 and the justifier key 35 is depressed, the escapement pinion 18 will be incapable of rotation by reason of the escapement pawls not being in released position, with the result that the rack 14 will be held immovable. However, the carriage 10 is still under the influence of the spring motor 16 and, through the link 20, the carriage exerts a force tending to rotate the bell crank

19 in a clockwise direction. Thus, when the key 35 is depressed, the carriage spring drum 16 being stronger than the spring 27, bell crank 19 will rotate track 22 counterclockwise. This movement will rotate the pinion 24 and the locking disc 25 clockwise an extent which is determined by the number of letter spaces remaining for the carriage 10 to move before the right hand marginal stop arrests the carriage.

For example, if the operator terminates the line two letter spaces from the marginal position then the carriage will move two more letter spaces when the key 35 is depressed and will displace the track 22 horizontally or counterclockwise to a position such as Fig. 2. When the key 35 is released, the locking pawl 28 will lock the disk 25 in its new position, holding the track 22 in the position of Fig. 2. The carriage is now returned and will travel to the right back to the position of Fig. 1 in which it is arrested by the usual left hand marginal stop. However, the track 22 will have been set at a small angle to its former position. In order to prevent feeding the tape T on the carriage return which occurs after the line has been written in draft form, any suitable means may be provided to lock temporarily the tape feed roller 33 in the patent or the tape may be fed by hand. The operator now raises the arms 12 and proceeds to retype the line, copying it from the tape T. As the carriage moves from right to left with the track 22 set at an angle, the carriage 10 will be moved to the left relative to the rack 14 a very small increment with each letter spacing movement of the rack 14. This is due to the fact that the shoe 21 will be progressively moved forwardly or downwardly in Fig. 1 as it travels to the left, thereby imparting a clockwise rotation to the bell crank 19 which will tend to push the carriage 10 a little further with each movement of the rack 14. The bell crank 19 is proportioned so that the leverage ratio for the angular displacement of the track 22 is just sufficient to bring the line out even. Thus, when the operator finishes typing the line, the right hand end of the line will conform to the desired right hand margin. If the line as first written terminates say at one letter space distance from the margin, the track 22 will be set at only a small angle since the carriage 10 will move only one letter space in setting the track 22. On the other hand, if the line is terminated, say ten letter spaces from the desired margin, then the track 22 will be set at ten times as great an angle and will produce ten times as much rotation of the bell crank 19 in retyping the line.

After the operator finishes typing the line the second time she will return the carriage and press the justifier key 35 again to reset the rack 22 to the position of Fig. 1 and will then lower the arms 12 in readiness for typing the next line in draft form.

No specific structure for feeding the tape T is disclosed and the patent is cited merely to show a conventional typewriter having suitable means for supporting the tape T along the writing line which permits the tape to be raised out of the way when the line is retyped. If desired the tape may be fed by grasping the tape to the left of the left hand arm 12 and drawing the tape to the left far enough to bring a fresh portion between the arms 12.

While there have been shown and described and pointed out the fundamental novel features of the invention, as applied to a preferred embodiment, it will be understood that various omis-

sions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a justifying typewriter, a platen carriage, a feed rack mounted in said carriage for limited movement relative to the carriage in a character spacing direction, an inclinable track normally positioned parallel with said rack, a releasable indexing device for holding said rack in different positions of inclination, a stop for aligning the track in its normal parallel position, resilient means for holding said track in said normal parallel position, a key for releasing said indexing device to permit inclination of the track in relation to said carriage; a lever pivotally connecting said carriage and said rack and having a sliding pivotal connection with said track, said sliding connection being effective to cause said carriage to feed progressively greater extents than said rack as the inclination of said track increases; and power means connected to said carriage for driving the latter in character spacing direction, said power means being effective, when said indexing means is released by said key with the carriage at a given line end position, to move the carriage to a marginal position and to

transmit movement through said lever to said track to incline the latter in proportion to the distance the carriage moves to the marginal position.

5 2. In a justifying typewriter, a carriage; carriage feed mechanism, including a feed rack mounted in the carriage for movement relative to said carriage in a letter spacing direction and a power device connected to the carriage for moving the carriage in letter spacing direction; feed controlling means interconnecting said carriage and rack for varying the extent of said relative movement including an inclinable track settable to different angles to vary letter spacing in proportion to the angle of inclination of said track, said power device normally tending to rotate said track in a direction to increase said angle of inclination; an indexing device for holding said track in its different set positions, and a justifier key for releasing said indexing device to permit said power device to set said track.
